HANDLE FOR LUGGAGE

Joseph Y. Pelavin, North Bergen, N.J., assignor to Lark Luggage Corporation

Filed Mar. 1, 1974, Ser. No. 447,435

Term of patent 14 years

Int. Cl. D8—06

U.S. Cl. D8—154

FIG. 1 is a front perspective view of a handle for luggage, showing my new design;

FIG. 2 is a front elevational view thereof;

FIG. 3 is an end view thereof, the opposite end being similar;

FIG. 4 is a top plan view thereof; and

FIG. 5 is a bottom plan view thereof.

I claim:

The ornamental design for a handle for luggage, as shown.
